UNITED STATES PATENT OFFICE

149,596

DESIGN FOR A ROLLER BOX TOOL

William E. Twamley, Providence, R. I., assignor
to Brown & Sharpe Manufacturing Company,
a corporation of Rhode Island

Application June 12, 1946, Serial No. 130,643

Term of patent 14 years

(Cl. D54—14)

To all whom it may concern:

Be it known that I, William E. Twamley, a citizen of the United States of America, residing at Providence, county of Providence, State of Rhode Island, have invented a new, original, and ornamental Design for a Roller Box Tool, of which the following is a specification, reference being had to the accompanying drawing, forming a part thereof.

Fig. 1 is a top plan view of a roller box tool showing my new design;

Fig. 2 is a side elevational view thereof;

Fig. 3 is a view of one end;

Fig. 4 is a view of the other end thereof; and

Fig. 5 is a perspective view thereof.

I claim:

The ornamental design for a roller box tool, substantially as shown.

WILLIAM E. TWAMLEY.
